(57) **CLAIM**

The ornamental design for a halogen flood light, as shown and described.

DESCRIPTION

FIG. 1 is a front elevational view of a halogen flood light showing my new design, wherein the lens has a pebbled surface finish;

FIG. 2 is a left side elevational view of the flood light from FIG. 1;

FIG. 3 is a rear elevational view thereof;

FIG. 4 is a right side elevational view thereof;

FIG. 5 is a top plan view thereof;

FIG. 6 is a bottom view thereof;

FIG. 7 is an upper rear perspective view of the floodlight of FIG. 1 showing the rear, side and top; and,

FIG. 8 is bottom rear perspective view of the floodlight of FIG. 1 showing the rear, side and bottom.
